STATUE DRESS

Albert A. Saverin, Guttenberg, N.J., assignor of fifty percent to Anthony J. Sullivan, West New York, N.J.

Application June 3, 1959, Serial No. 56,195

Term of patent 14 years

(Cl. D29—26)

Fig. 1 is a front elevation of the new design for statue dress, the statue being shown in dotted lines for illustration purposes only;

Fig. 2 is a rear elevation of the new design shown in Fig. 1; and

Fig. 3 is a top plan of the design shown in Fig. 1.

The border areas indicated in the drawings are intended to show stitching which extends outwardly on each side of the marginal strips and is sewn through the strips so that the thread appears as dotted areas between the margins at the locations shown.

I claim:

The ornamental design for statue dress, as shown and described.
